TELEPHONE SYSTEM

Hans Dreyer, Berlin-Charlottenburg, Germany,
assignor to Siemens & Halske Aktiengesellschaft of Wernerwerk, Siemensstadt, near Berlin, Germany

Application July 22, 1937, Serial No. 154,981
In Germany July 30, 1936

13 Claims. (Cl. 179—18)

The present invention relates to a circuit arrangement for control switches in telephone systems. It aims at a better utilization of the contacts of the control switch thereby realizing an increase in efficiency in control switch working. The calls initiated over control switches are so far as is possible to result in the establishment of a call even during peak periods in the traffic. In addition a signal is to be sent to the calling station in the event of the group of lines in the desired traffic direction being engaged without it being necessary to use more contacts in the control switches.

In the known arrangements overflow repeaters were arranged at auxiliary contacts of the control switch which, in the event of all the lines of the group from which if another traffic direction had been dialled the control switch would have been controlled, being busy, were seized by the control switch. These overflow repeaters then transmitted a switching-over signal for controlling the control switch when the digits characterizing particular traffic directions were dialled.

In the event of a group of lines controlled by an overflow repeater after the switching over operation, being busy, it is necessary to transmit a busy signal to the calling station. For this signalling operation the arrangement according to the invention uses the same contact set of the control switch as that to which the dummy repeater is connected.

Moreover, the devices which may be reached over the overflow positions of the control switch are arranged to receive the characteristic number of the desired traffic direction in such a manner that these devices are associated in common with a plurality of groups of control switches.

Another advantageous feature of the invention consists in the provision of a plurality of groups of control switches such that control repeaters are reached over the overflow positions of the control switches of one group of lines which can be reached directly from another group of control switches and have access to succeeding devices.

In place of busy repeating devices, in the event of all the lines of a group which are reached after a switching over operation being busy, auxiliary paths can conveniently be connected up at the overflow positions, these auxiliary paths containing switching devices (connecting switches) which may be reached directly from the control switches of other groups of lines.

In Figs. 1, 1A, 2, and 2A embodiments of the invention are shown, the latter not being limited

to these embodiments. Only the details necessary for understanding the invention are shown. Figs. 1 and 1A, when placed side by side, show two control switches D and D_I having access in common to a repeater UGW for outgoing calls, to a selector switch JGW for local calls and to an overflow device BL.

Figs. 2 and 2A, when placed side by side, show a control switch D_I normally having access only to certain switching selectors, such as UGW₁II and to certain local selectors, such as JGW₁0I; a similar control switch D_{II} is shown normally having access only to different switching selectors, such as UGW₅II and to different local selectors, as JGW₅II. Also shown are two change-over circuits W₁ and W₂II by means of which either control switch may gain access to a switching selector or a local selector normally accessible only to the other control switch.

Referring now particularly to Figs. 1 and 1A, when a calling station initiates a call the switch D after having been seized over selecting devices which are not shown sets itself on a free device UGW by a free stepping operation. During this setting the switch D is controlled over wiper cd. After the repeater UGW has been connected up the subscriber receives dial tone in the known way. The subsequent dialling determines whether the call is to proceed over the repeater UGW or whether the switch D must bring about the switching operations in order to connect up a free device JGW. If the calling station dials the number of an exchange which is reached over the line L_a2 and L_b2 the call is set up in known way over this line. If, however, the subscriber dials a digit characterising internal calls a control impulse is transmitted over the line L_d2 by devices in the control repeater UGW, whereupon the switch D searches for a free group selector JGW under the control of wiper dd.

If when a call is initiated all the outgoing lines which lead to the control repeater UGW are engaged the wipers of the switch D pass to position 17. In this position a device provided with a numerical impulse receiver is seized over wiper cd, this device being so constructed that the calling station receives the busy signal if an external traffic direction has been dialled to indicate that all the lines in this direction are engaged. If, however, the calling station dials an internal number the device seized over cd in position 17 effects the transmission of a control impulse over the lead L_d4 whereupon the switch D is started up in order to connect up a free connecting path in the desired direction under the control of

wiper *dd*. If a free path in this direction is not found the switch can again pass to position 17 from which it has already been advanced. In this position the calling station now receives a busy signal. On the call being abandoned the switch D is advanced from position 17 to position O. If when the call is initiated a free control repeater UGW is found by the switch D and this performs its switching-over operation the calling station similarly receives a busy signal when the switch D is set in position 17 if the latter has not previously found a free internal group selector.

The device which is reached over position 17 can be provided in common for a plurality of 15 switches. Figs. 1 and 1A show such a device associated with two groups (I and II) of switches, one switch of each group being shown. The switch of the group I has the reference D and the switch of the other group II has the reference D1. The switches of the group II are constructed in the same way as the switches of the group I of which the switch D is shown in detail. The establishment of a call will now be explained with reference to this switch.

The arrangement shown in Figs. 1 and 1A is seized by the application of battery potential to lead Lc. Whether this battery is applied by way of a preselecting device or by a numerical impulse receiver is immaterial to the operation of the arrangement shown. The following circuit is established: earth, battery (not shown), lead Lc, contact 5t, winding I of relay R, contacts 10u and 11g and earth. In this circuit relay R energizes and operates contacts 1r, 2r, and 3r. The testing wiper cd of the switch D is connected up by contact 1r. The interrupter device Un is connected to the rotary magnet Dw of the switch over contacts 2r and 4t. The magnet Dw receives impulses from the repeater Un so that the 40 wipers ad, bd, cd, dd and ed are advanced stepwise. Contact 3r prepares for the connection of winding I of relay U. When the switch D finds a free line in the group to be tested over wiper cd, for example the line La2—Ld2, the following 45 testing circuit is established: earth, battery (not shown), lead Lc, windings I and II of relay T, contact 9u, winding II of relay R, contact 1r, wiper cd, lead Lc2, common switching means in the control repeater UGW, which are not shown and earth. In this circuit relay T and other switching means in the lead Lc2, which are not shown, energize. The switch D is brought to rest by the opening of contact 4t. Contact 5t short-circuits winding I of relay T. Contacts 6t and 7t switch through the leads La and Lb (the speaking leads). The circuit for winding I of relay R is broken at contact 5t, but the relay does not release since its winding II holds up in series with winding II of relay T. The calling subscriber now receives dial tone in the known manner whereupon he transmits the impulse train or trains forming the call number. The impulses produced at the calling station are taken up by relay A and are transmitted to succeeding devices in the known way. Relay B remains up during the impulse transmission over the leads La—La2 and Lb—Lb2. When the impulses are received by relay A a switching device for example a discriminator switch (not shown) in the control repeater UGW is operated and effects certain switching operations if particular numbers are dialled. If the calling station dials digits characterizing a call passing over the line La2, 70 Lb2 (external) the special switching device in

the repeater UGW does not effect any switching operation. After dialling numbers which characterize an internal call, however, the contact st is temporarily closed by the switching device arranged in the control repeater UGW. This applies earth to lead Ld2 whereby relay U in the switch D is energized in the following circuit: earth, contact st, lead Ld2, wiper dd, windings III and II of relay U, contact 5t, lead Lc, battery (which is not shown) and earth. Relay U operates its contacts and at contact 9u breaks the connection between leads Lc and Lc2. The device UGW is thereby released. Relay T releases immediately while relay R does not since it is a slow-to-release relay. Relay R establishes a locking circuit over its winding I passing over contact 5t, winding I of relay R and the operated contact 10u to resistance Wil and earth. After relay T has released contact 4t is closed so that the magnet Dw receives impulses from the interrupter Un. Relay U is connected to earth over its winding I and contacts 3r and 8u and is thus held energized by the battery applied to lead Lc. When the switch D finds a free line, for example La3—Ld3 in the group tested over the wiper dd, the following testing circuit is established: battery, lead Lc, windings I and II of relay T, contact 9u, winding III of relay U, wiper dd, lead Ld3 and earth. Relay T brings the switch D to rest by opening contact 4t and by closing contacts 6t and 7t switches the leads La and Lb through. The switching over of contact 5t guards the line which has been found. Relay R is deenergized, its circuit being broken at contact 5t. Relay U, however, remains energized over wiper dd. The calling station is now in the position to deenergize relay A2 intermittently by transmitting impulses and to control switches which are not shown, relay B2 remaining operated.

If the call is to be released this can be brought about by disconnecting the battery connected to lead Lc whereupon relays T and U release. Through the closing of contact 4t the magnet Dw is again connected to the interrupter Un, whereupon the switch is stepped until wipers ad to ed reach position O. The release can just as well be brought about by breaking the lead Ld3 in dependence upon relays A2 and B2.

If the switch D is started up by a call at a moment at which free lines (control repeaters) cannot be reached over wiper cd, the switch D is advanced to position 17. In this position the following testing circuit is set up: earth, switching means in the repeater device BL, which are not shown, contact 14y1, relay X1, lead Lc4, wiper ed in position 17, contact 1r, winding II of relay R, contact 9u windings II and I of relay T, lead Lc, battery and earth (not shown) on the lead Lc. In this circuit relays T and X1 energize. Relay T brings the switch D to rest in the manner already described. Relay R holds up over winding II. Relay X1 operates contacts 14x1, 15x1 and 16x1. Contacts 14x1 and 15x1 serve to connect the leads La4 and Lb4 to relays A3 and B3. Contact 16x1 connects lead Ld4 to contact 22ug.

A signal is transmitted to the calling station indicating that dialling can commence. Relays B3 and A3 are energized over the loop between leads La and Lb. When the dial switch is operated at the calling station relay B3 holds up while relay A3 is impulsively deenergized by the breakages in the loop which occur during impulsive dialling at the calling station. Through the energizing of relays A3 and B3 when the calling sta-

tion is connected to the device BL, contacts 17a3, 18b3 and 19b3 are operated. Since contact 17a3 opens before contact 18b3 closes the rotary magnet CH of the stepping switch disposed in the device BL is not energized. Contact 19b3 disconnects the interrupter Un2. When now the calling station operates the impulse sending device, the rotary magnet CH and the slow relay V are energized by the intermittent closing of contact 17a3. The rotary magnet CH steps the wipers 2ch and 3ch. Relay V which is a slow-to-release relay does not release during the stepping of the switch CH. Consequently contact 20v remains open during the reception of an impulse train. When the impulsing is over relay A3 remains energized for a prolonged period. This causes relay V to release. Relay V closes contact 20v so that earth is connected to wiper 2ch. According to the setting of switch CH either relay BE or relay UG is now energized. If the switch CH has been set by the digit 2 for example, relay BE energizes on release of contact 20v. Relay BE operates contact 21be so that the busy signal Bes2 is connected to winding II of relay A3 over contact 21be and the condenser Ko. This busy signal is transmitted inductively to winding I of relay A3 so that the calling station receives the busy signal. The calling station only receives this busy signal after dialling a call number which characterizes a traffic direction (external) which was tested (over wiper cd) unsuccessfully when the call was initiated.

If, however, after the device BL has been connected up the subscriber dials the digit which characterizes an internal call, wiper 2ch of switch CH passes to position 3. In this position relay UG is energized after relay V has released. Relay UG closes contact 22ug thereby applying earth over contacts 22ug and 16x1, lead La4 and wiper dd of windings III and II of relay U. Relay U thereupon energizes in the manner already described. The switch D is started up again and tests for a free internal connecting line under the control of wiper dd.

The setting of the switch CH in the rest position takes place on the deenergization of relays A3 and B3 in that the interrupter Un2 is then connected over the contact bank and wiper 3ch to the magnet CH through the closing of contact 19b3. In this circuit relay V is energized again so that the earth connected to wiper 2ch is disconnected at contact 20v. The switch then proceeds to position O, without influencing any switching means during its stepping. In position O the circuit for the magnet CH and relay V is broken at 3ch. On the further stepping of the switch D relay X1 is also deenergized if this is to be switched over onto local lines so that the busy signal repeater Ue1 may be seized over contact 16x1 by the operation of relay Y. It is obvious that instead of the switch CH, which is only diagrammatically represented and which selects the traffic direction by means of an impulse train, a switch may be provided which differentiates between the traffic directions after a plurality of digits have been dialled.

If after the transfer operations just described the switch D does not find a free line among the internal lines, it is brought to rest in position 17 in which relay Y1 is energized. Relay Y1 then operates its contacts and connects the transformer Tr2 to leads La4 and Lb4 over contacts 12y1 and 13y1. The calling subscriber receives the busy signal from the transformer over leads La and Lb. When the connection is released by

the disconnection of battery from lead Lc after the busy signal has been transmitted, relays T and U in the switch D release. In the repeater Ue1 relay Y1 releases. The switch D passes to position O in the manner already described. While the repeater device Ue1 is transmitting the busy signal contact 14y1 is open so that relay X1 cannot energize and thus the transmission of the busy signal cannot be interfered with.

If the busy signal repeater Ue1 is seized by a switch of the group I the repeater BL can be connected up over a switch of group II and can bring about the switching over operations and the transmission of the busy signal. Also the busy signal repeater Ue2 can transmit a busy signal during the time that the busy signal repeater Ue1 is in operation.

If a switch of the group II, for example switch D1, is operated after a control repeater UGW has been reached over this switch and if it does not find a free internal line after the wiper dd2 has been connected up relay Y2 is energized over contact 23x2 when the switch is brought to rest in position 17. Switch D1 is brought to rest in the same way as described in connection with the switch D of group I. Relay Y2 on energizing, operates contacts 29y2, 30y2 and 31y2. The calling station receives the busy signal over contacts 29y2 and 30y2, while by the opening of contact 31y2, relay X2 is prevented from energizing and this prevents the transmission of busy tone being interfered with by the repeater Ue2. If a switch in group II does not find a free control repeater UGW when a call is initiated, relay X2 is energized when the switch (for example switch D1) is set in position 17, over wiper cd2. Relay X2 then switches through the leads associated with wipers ad2 and bd2 over contacts 23x2 and 21x2, whereupon the overflow repeater BL causes a busy signal to be transmitted after the characterizing impulse train has been received if an external call is characterized, or produces a control signal if an internal call is characterized. The switching operations which take place are the same as have been described in connection with the setting of the switch D of the group I.

In Figs. 2 and 2A another embodiment of the invention is shown. ID1 represents a control switch which is equipped similarly to the switch D in Fig. 1. This is a switch belonging to a group of similar switches referred to by the reference I. In contradistinction to the switch D in Fig. 1 this switch does not possess a rest position. The special overflow position of this switch is not situated at the end of the contact bank but in the middle. This position is indicated by the reference 2. A ten-point switch is shown but the switch can possess either more or fewer contacts. In the left hand bottom corner of the drawings a further switch is shown which is similar in its construction to the switch ID1. This switch has the reference IDII and belongs to a group of switches II. Over the switch ID1 and IDII switching group selectors and internal group selectors are reached. On initiating a call the switches ID1 or IDII are set on a switching group selector whereupon the transmission of an exchange characterizing digit on the part of the calling station determines whether the call is to proceed over the switching group selector or whether an internal group selector is to be seized by switching operations at the switches ID1 or IDII. The switching group selectors have the reference UGW and the internal group selectors the reference JGW. The addition of a Roman number indicates over which

group of control switches the corresponding group selectors can be reached directly. Over the overflow position 6 the control switches have access both to switching group selectors and also to internal group selectors. These switching and internal group selectors reached over the overflow positions 6 of the switches of group I may also be reached over control switches of another group, for example of group II. The connecting of a control switch or an internal group selector over an overflow position of the control switch is effected by a change-over circuit indicated by W_{eI} for the group I of control switches and W_{eII} for the group II of control switches.

When the switch 1DI is seized by a calling station it is set on a free switching group selector UGW1I to UGW5I. The setting of the switch 1DI is initiated by the energizing of relay R over winding I. This relay energizes in the following circuit on the connection of battery (not shown) to lead Lc: earth, battery, lead Lc, contact 5t, winding I of relay R, contacts 10u and 11g and earth. Relay R energizes and starts up the switch by energizing the rotary magnet 1DW over contact 2r. Contact 3r connects winding I of relay U to lead Lc in preparation. Contact 4r prepares for the testing operation by connecting windings I and II of relay T to wiper cdI. When the switch 1DI finds a free switching group selector, for example, the switch UGW4I, the following testing circuit is established: battery on lead Lc, windings I and II of relay T, contact 9u, winding II of relay R, contact 4r, wiper cdI in position 4, seizing means and earth (not shown) in the switching group selector UGW4I. Relay T energizes and by opening contact 4t brings the switch 1DI to rest. Contacts 6t and 7t switch through speaking leads while contact 5t guards the switch which has been found by short-circuiting winding I of relay T. Moreover, contact 5t connects winding I and III of relay U to wiper ddI. When now the calling station operates the dial switch a discriminator, known per se. is started up in the switching group selector UGW4I, the setting of which determines whether the call is to pass over the switching group selector or whether an internal connecting line is to be connected up by controlling the switch 1DI. If in the case of the present call the number characterizing an internal call is dialled earth is temporarily connected to contact 4 of wiper ddI, by the discriminator switch in the switching group selector UGW4I. Relay U in the switch 1DI is consequently energized. Relay U operates contact 8u and thus establishes a locking circuit for winding I of relay U via the lead Lc. Relay T is deenergized because its circuit is broken at contact 9u. Relay R which is a slow-to-release relay holds up over winding I and the back contact 5t and contact 10u which has been switched over meanwhile. The rotary magnet 1DW is subjected to current over contact 4t so that the wipers of the switch 1DI are advanced stepwise by the magnet 1DW. The switch 1DI does not test on contact 6 by way of wiper ddI during this stepping because the lead Ld1 is broken at contact 19jnI. The switch passes to position 1 and can search for a free internal group selector belonging to the group I over this position and the following positions 3, 9 and 10. If it finds, for example, the internal group selector JGW10I to be the first free switch relay T energizes in the following circuit: earth (not shown) on lead Ld10 in the group selector JGW10I, contact 10 in the contact bank asso-

ciated with wiper ddI, winding III of relay U, contact 9u, windings II and I of relay T and battery on the lead Lc. Relay T energizes and at contact 4t breaks the stepping circuit of the switch 1DI and at contacts 6t and 7t switches through the calling line. The line which has been found is guarded by contact 5t; relay R releases. Relay U, however, remains energized.

Other switching operations occur if when a call is initiated all the outgoing lines in the group to be tested are engaged. In this case the overflow position (contact 6) in the switch 1DI is used. If, for example, all the switching group selectors of group I of the controlling switches are engaged relay EXI is energized over contacts operated when the group selectors are taken into use, for example, over contacts 1ugw1, 2ugw1, etc. Relay EXI has closed contact 18exI. In this case the switch 1DI steps until wiper cdI finds contact 6. It is immaterial from which position the switch is started up for any testing on the contacts to which internal group selector are connected is not possible because wiper ddI is not yet connected up. When the switch 1DI reaches position 6 the following circuit is set up: battery, lead Lc, windings I, II of relay T, contact 9u, winding II of relay R, contact 4r, wiper cdI, contact 6, lead Lc1, contacts 18exI and 17y, relay X, lead Lc3, switching means connected to lead Lc5, which are not shown, and earth.

In this circuit relay T energizes in the switch 1DI and brings the switch to rest while switching through the speaking leads. Relay X also energizes and operates contacts 12x, 13x and 14x. The switching over of contact 14x prevents the internal group selector JGW10II from being seized over the auxiliary rest position 6 of the switches of group I. Moreover, it causes lead Ld3 to be connected to contact 6 at wiper ddI over which the control impulse is later to be transmitted. The calling station is now connected to the switching group selector UGW5II which can be reached directly over contact 5 of the control switches of group II. Only one of these control switches of group II is shown, namely switch 1DII and this only diagrammatically. When contacts 6t and 7t are closed on the setting of the switch 1DI, relays A3 and B3 in the switching group selector UGW5II are energized by the loop established by the calling station between leads La and Lb. The relays A3 and B3 operate their contacts. Relay A3 operating slightly before relay B3. Contact 20a3 opens slightly before contact 22b3 closes. Contact 23b3 disconnects the interrupter Un2 from the bank of wiper 3s of the discriminator switch MS at the switching group selector UGW5II. The group selector UGW5II itself is not shown. It can be a switch of any known construction. Its setting is effected under the control of relay A3 which also sets the discriminator switch MS.

Relay B3 remains energized during the impulses on the part of the calling station. Relay A3, however, responds to the impulses. Each time the relay A3 releases the stepping magnet S of the discriminator switch MS receives current so that the discriminator switch takes a step forward on each impulse. The group selector which is operated by the same impulse train is not shown since it has no bearing on the explanation of the present invention. During the reception of impulses the magnet S is impulsively operated but relay V remains energized so that contact 21v remains open while the impulses are

being received. If the subscriber dials an exchange number characterizing an external call, the call passes over the wipers of the switching group selector connected to leads La5 and Lb5 without the discriminator switch MS exercising any switching function.

On the termination of the characterizing impulse train relay V releases, whereupon contact 21v is closed. To the contacts of wiper 2s which are reached if an external traffic direction is dialled no switching means are connected. Obviously after the setting of the switching group selector which is not shown on a different connecting line switching means can become operative to disconnect potential from the stepping magnet S so that subsequent impulse trains which influence relay A3 for the purpose of setting succeeding switches no longer produce a setting of the discriminator switch MS.

If, however, the subscriber dials a digit for setting the discriminator switch which is characteristic of an internal call wiper 2s of the discriminator switch is set on contact 4. When relay V releases at the end of this characterising impulse train relay UG is energized in the following circuit: earth, contact 21v, wiper 2s, relay UG, battery and earth. Relay UG energizes and closes contact 24ug. Earth is consequently applied to the lead Ld5 whereupon relay U is energized in the switch 1DI. Relay U now influences the switch 1DI in the manner already described so that the switch searches for a free outgoing line leading to an internal group selector over wiper ddI, relay T being deenergized. Through the opening of the speaking leads at contact 6t and 6t when the switch 1DI is advanced from position 6, relays A3 and B3 in the switch group selector UGW5II are deenergized. Hereupon the interrupter Un2 is connected to the rotary magnet S and relay V over contacts 23b3 and wiper 3s. The rotary magnet S now receives impulses, relays V being energized, until wipers 2s and 3s have reached position O. When wiper 2s leaves position 4 relay UG deenergizes so that contact 24ug is opened. When the switch 1DI is advanced from contact 6 or when contact 9u is switched over relay X is deenergized. Contacts 12x and 13x are consequently opened and contact 14x closed (normal position). It is clear that when the wipers 2s and 3s are set in the rest position the numerical impulse receiver connected to La5 and Lb5 is released.

When after the switch 1DI has been set on one of the contacts 1 to 5 switching over takes place a free line is sought over contacts 7 to 10 of switch 1DI, wiper ddI being connected up. If there are no free lines connected to these contacts the switch 1DI tests in position 6. In this position the following circuit is established: battery, lead Lc, windings I and II of relay T, contact 9u, winding III of relay U, wiper ddI, contact 6, lead Ld1, contact 14x, contact 19nI, relay Y, lead Ld2, switching means in the lead Lc4 which are not shown and earth. Relays T and Y energize. Relay T brings the switch 1DI to rest in the manner previously described. Relay Y switches through the speaking leads at contacts 15y and 16y. Contact 17y is opened and prevents the switching group selector UGW5II being seized over contacts 6 of a switch of the group I. The switch 1DI was able to test at contact 6 because relay JNI is energized. Relay JNI energizes when all the internal group selectors JGW1I to JGW10I of the group I are engaged as is assumed in the present example.

The calling subscriber on the line La/Lb is now connected to the internal group selector JGW10II by the aid of the change-over circuit WeI, over which the internal traffic of the group II over contact 10 of the switch 1DII and following switches of the group II normally passes. Setting of the internal group selector JGW10II takes place with the aid of relays A and B in the known way by the calling station transmitting impulses. The group selector itself is not shown because the present invention is not concerned with its construction. If the switch JGW10II is already seized over a switch of the group II when the switch 1DI is set in position 6 the latter switch again tests over wiper ddI because guarding potential is connected to lead Lc4 by applying over wiper ddII. Wiper ddII is connected to switching means which are identical with the switching means connected to lead Ld1 of the switch 1DI.

The control switches of group II also have access over their auxiliary rest positions (position 6) to a change-over circuit indicated in the drawings by WeII. This change-over circuit is equipped in the same way as the change-over circuit WeI of the group I of control switches. The change-over circuit WeII gives access to the control switch UGW4I if when a call is initiated for example over the control switch 1DII (which is indicated) all the switching group selectors which can be reached over contacts 1 to 5 are engaged. In this case the switching group selector UGW4I causes an external connecting line to be connected up if the calling station dials the number of such a line. If, however, after the switch UGW4I has been connected up the calling party dials the number characterizing an internal call the switch 1DII is switched over so that it searches for a free outgoing line to an internal group selector over the contacts 10 to 7. If in the normal progress of a call all the internal group selectors which are connected to contacts 7 to 10 of the switch 1DII are engaged when the switch 1DII has been switched over the switch likewise passes to position 6. In this position it is brought to rest and the switch JGW10I is connected up. This is an internal group selector which is normally reached from the control switches of group I over their contacts 10. The calling station then establishes the desired call over this internal group selector.

By suitable grouping it is, of course, possible to arrange the system so that even in the normal case a control switch of one of the groups has access over individual contacts to switches of the other group by applying known group multiplying, etc.

If all the external outlets and the auxiliary switches UGW5II are engaged in the overflow 6 of group I of the control switches relays EXI and K are energized. These relays then control relay G over contacts 25exI and 26k which by opening its contact 11g prevents any seizure over the lead Lc.

What is claimed is:

1. In an automatic switching arrangement, a control switch having access to a plurality of lines, said lines being arranged in groups accessible to the wipers of said switch, means for seizing said switch and for causing said wipers to automatically search for an idle line in one group, an overflow device, means operated to seize said device over the wipers of said switch when all the lines in said one group are busy, and means in said device operated over said wipers for at times

causing the wipers of said control switch to search for an idle one of said lines in another of said groups.

2. An automatic switching arrangement as claimed in claim 1, wherein said means in said device at other times reverts a signal over the wipers of the switch to indicate that a connection is unobtainable.

3. An automatic switching arrangement as claimed in claim 1, wherein said means in said device at other times controls the extension of a connection through said device.

4. In an automatic switching arrangement, a control switch having access to groups of lines, an overflow device accessible to said switch, means for seizing said switch, for causing same to automatically search for an idle line in one of said groups, and, if all of the lines of said one group are busy, to connect with said overflow device, means for transmitting digits to said device, means therein responsive to certain of said digits for causing the extension of a connection through said device or responsive to certain other of said digits for causing said control switch to search for an idle one of said lines in another one of said groups.

5. In an automatic switching arrangement, a control switch having access to groups of lines, an overflow device accessible to said switch, means for seizing said switch, for causing same to automatically search for an idle line in one of said groups, and, if all of the lines of said one group are busy, to connect with said overflow device, means for transmitting digits to said device, and means therein for causing or preventing a further automatic searching operation of said control switch in accordance with certain of said digits.

6. In an automatic switching arrangement, a control switch having access to groups of lines, an overflow device accessible to said switch, means for seizing said switch, for causing same to automatically search for an idle line in one of said groups, and, if the lines of said one group are busy, to connect with said overflow device, means for transmitting digits over said switch to said device, means in said device responsive thereto for causing said control switch to search another group, said switch effective to connect with said overflow device again if said other group is busy, and means operated when said device is again connected with to transmit a signal indicating that a line is unavailable.

7. In a switching system, an automatic switch whose wipers have access to a plurality of lines, means for making any of said lines busy, means for causing said switch to search for an idle line and, when one is found, extend a connection thereto over its wipers, and means for controlling said switch revertively over said wipers and said last line, thereby to cause said switch to move its wipers from said last line in search for another idle line.

8. In a switching system, an automatic switch, equipment accessible to said switch, means for extending a connection over the wipers of said switch to said equipment and for transmitting thereto over said connection one or more digits, means in said equipment for at times, in dependence upon the value of said one or more digits, initiating a hunting movement of the wipers of said switch, and means in said equipment for at other times extending said connection through said equipment.

9. In a switching system, an automatic switch, equipment accessible to said switch, means for extending a connection over the wipers of said switch to said equipment and for transmitting thereto over said connection one or more digits, and discriminating means in said equipment for making a determination from said digits alone, said last means effective at times to initiate a movement of the wipers of said switch in dependence upon said determination.

10. In a switching system, two groups of trunks, a distributor having access to said trunks, means for operating said distributor to seize an idle trunk of one of said groups and for transmitting to said trunk over said distributor one or more digits, means in said trunk for at times causing the switch terminating the trunk to extend a connection in accordance with said digits, and other means in said trunk effective at times in accordance with said digits to cause said distributor to disconnect from said trunk and seize an idle trunk of the other of said groups.

11. In a switching system, two groups of trunks, control equipment, a distributor having access to said two groups of trunks and to said control equipment, means for operating said distributor to seize an idle trunk in one of said groups if there is an idle trunk available in said one group or to seize said control equipment if no trunk is available in said one group, means for transmitting over said distributor one or more digits, and means in said control equipment, if same is seized by said distributor, for receiving said one or more digits and making a determination therefrom, said control equipment thereupon effective at times in accordance with said determination to cause said distributor to seize an idle trunk in the other of said groups.

12. In a telephone system, outgoing lines, local lines, a distributor having access to said lines, means for seizing said distributor to extend a call, said distributor effective responsive to said seizure to search for an idle one of said outgoing lines and extend a connection thereto, discriminating means associated with said outgoing line for determining whether the call is local or outgoing and, if same is local, for causing said distributor to search for an idle one of said local lines and extend a connection thereto.

13. In a telephone system, outgoing lines, local lines, discriminating equipment, a distributor having access to said lines and to said equipment, means for seizing said distributor to extend a call, means responsive to said seizure for causing said distributor to search for an idle one of said outgoing lines and extend a connection thereto, or, if no one of said outgoing lines is idle, to extend a connection to said discriminating equipment, and means in said equipment for determining whether the call is local or outgoing and, if same is local, for causing said distributor to search for an idle one of said local lines and extend a connection thereto.

HANS DREYER.
